CONCRETE MIXER

John W. Lendved, Wauwatosa, Richard B. Rousseau, Brookfield, and Nolan K. Rhoades, Beloit, Wis., assignors to Chain Belt Company, Milwaukee, Wis., a corporation of Wisconsin

Filed July 27, 1959, Ser. No. 56,947

Term of patent 14 years

(Cl. D14—3)

FIG. 1.

FIG. 3.

FIG. 2.

FIG. 1 is a view in perspective of a concrete mixer embodying our new design, taken looking toward the right and rear sides thereof;

FIG. 2 is another view in perspective of the mixer, taken looking toward the left side and forward end thereof; and

FIG. 3 is a top plan view of the concrete mixer.

The dominant features of our design reside in the portions shown in full lines and the truck shown in broken lines in FIG. 1 is included for illustrative purposes only.

We claim:

The ornamental design for a concrete mixer, substantially as shown and described.
